WATCHCASE CONSTRUCTION

Leopold Hoffer, Cincinnati, Ohio

Application July 16, 1936, Serial No. 90,941

6 Claims. (Cl. 58—90)

My invention relates to watchcases and more especially to watchcases of the simpler and smaller types, notably wrist watches, in which, as heretofore manufactured, the support for the winding and setting stem of the watch movement, in the watch case, has been inadequately provided for, and in which usually the closure therearound has been insufficiently provided against entrance of foreign matter to the watch movement.

The type of watchcases to which my invention is more especially directed usually are simply drawn up and formed of sheet metal, and for admitting the movement stem there is left simply an opening amply large without any attention to forming this opening in such a manner as to accurately receive the stem whereby it could afford an adequate bearing and an adequate closure around the stem. In many instances the shape of this opening is merely that which results from forming an opening in the blank and allowing this opening to change its form incident to the forming operation on the blank, so that the opening is very irregular in shape and must be provided so as to be amply larger than the stem on account of this irregularity of shape.

In instances where the opening receives the stem closely the extent of the bearing may be only that of the thickness of the sheet metal, which becomes worn away so that there is no longer a bearing or support for the stem, nor sufficient closure to exclude foreign substances from the case.

In any of these situations, with the stem not having a bearing in the watchcase in addition to its bearing in the watch movement, of which it forms part, the stem, in its extension from the watch movement out through the case, is liable to considerable deflection under the pressure of a winding operation, so that not only does the watch seem to be flimsily constructed, but there is actually an undesirable tendency for the stem to wear in its bearings in the watch movement, and the lack of the support of the stem increases the possibility of bending and breaking the stem.

To leave a considerable opening for the entrance of dirt, dust, and moisture, including perspiration of the wearer, of course greatly increases the depreciation of the watch movement from clogging, excessive wear, rust and corrosion of the movement parts, in addition to the damaging tendencies due to the lack of proper support of the stem above pointed out.

Furthermore in a large proportion of watchcases of the type with which my invention is es-

specially concerned, not only is the stem not properly supported but the crown is spaced out away from the exterior of the watchcase, either very noticeably, or at least to that extent that is necessary on account of there having been no attention given to forming the exterior of the case to an accurate bearing of the crown against it. The result of this is that the crown, as regards to its connection to the stem, is subject to considerable tilting strain in the operation of winding and therefore is liable to be bent out of proper position on the stem, or may even be, in time, broken from the stem.

It is the object of my invention to provide against the above defects found with the usual watchcases, so as to provide the stem with an adequate bearing, to provide adequate closure around the stem, and also preferably to adequately support the crown, so that the stem and crown will be supported against the strains of winding operations and so that durable bearing will be afforded in the watchcase for the stem.

My improved construction, though not limited thereto, is especially adapted for provision, by watch repairmen, in cases already constructed, of a support member which is made especially to fit the particular watchcase, in the manner hereinafter to be described.

Further objects will appear in the course of the following description, illustrated by the accompanying drawing, in which—

Fig. 1 is a front elevation of a three-piece wrist watchcase to which my invention is applied;

Fig. 2 is an enlarged edge elevation of the same, partly in section on the line 2—2 of Fig. 1; 35

Fig. 3 is a detail perspective view of the support member involved in my improved construction;

Fig. 4 is a perspective view of a three-piece watchcase of modified shape but of the same construction as that of Figs. 1 and 2 so far as my invention is concerned, the support member being shown above the watchcase, and the watchcase being only partially assembled or closed; and 45

Fig. 5, in a similar manner, illustrates a similar watchcase, but of two-piece construction, illustrating how my invention is embodied therein.

Referring to Figs. 1, 2 and 4, as showing watchcases of three piece construction, the center 10 of Figs. 1 and 2 or 10' of Fig. 4 has the usual back 11 or 11' and the bezel 12 or 12' carrying the crystal 13 or 13'. As is well known in the art, such a watchcase as illustrated is constructed for that mode of assembly. It will be under- 55

stood, however, that these details, and any other details of assembly of watchcase, pieces, or of their shape, do not materially affect my invention.

5 The part of the case with which my invention is intimately concerned is the stem opening 14 in the center 10 or 10'.

In Fig. 2 a watch movement 15 is shown mounted in the center 10 by means of case screws 16 in the usual manner. The winding and setting stem 17, usually considered as part of the movement 15, is received in and supported by the movement 15, but it is understood, as ordinarily provided, would be readily detachable from the movement in the course of inserting or removing the movement into or from the watchcase.

As previously explained, the opening 14 is not usually accurately formed in the relatively thin walls of the case center 10 or 10' and is formed 20 sufficiently larger than the stem to avoid necessity of accurately forming this opening. In illustrating, I have not shown the watchcase with this usual irregular opening but show it with an accurate circular opening aligned with the 25 stem bearing in the movement 15, the opening being relatively much larger than the diameter of the stem portion that passes through the opening; this size and accuracy having been provided as a part of the operation of embodying my invention in the watchcase of the usual less accurate construction.

30 Into this opening 14 is accurately fitted the stem and crown support member 18, which comprises a main hollow, cylindrical body portion having, at one end only, a relatively widely projected annular flange 19. The exterior of the body portion accurately fills the opening 14, the flange 19 closely abutting the exterior of the watchcase center 10 or 10' around the opening 35 14; and the cylindrical interior 20 forms the bearing for the stem while the top or outer surface of the support 18 forms a bearing for the under surface of the crown 21, preferably being of such diameter as to receive the greater 40 part of the area of this under surface. This support member 18 fits the opening 14 sufficiently tight to remain stationary in the center 10 or 10', and although the exterior surface 22 of the center 10 or 10' has only such accuracy as is 45 given in forming this center by the usual methods of large quantity production, it will be understood that the flange 19 will fit sufficiently accurately to give the support member 18 a firm bearing, so that it maintains an accurate relation 50 to the movement 15 and the stem 17 thereof.

55 The flange 19 also adds to the distance that must be traveled by foreign substances to enter the case, thus adding to the effectiveness of the closure formed around the stem.

60 Many of the watch movements have the stem 17 of the construction illustrated in Fig. 2 in which there is an enlargement or hub 23 unitary with the stem 17 immediately under the crown 21 and extending a considerable distance therefrom along the stem. This enlargement or hub 65 serves in the ordinary construction to reinforce the connection of the stem and its crown.

60 In addition to the movements incident to winding, it is of course understood that there is also 70 an axial movement of the stem to bring it into and out of position for setting the watch, and although this does not occasion nearly as much wear, it does create a condition in which lack of support leaves the stem and crown greatly exposed to the dangers of bending and breaking.

With regard to the wear in the bearing, if the usual watchcase only is allowed to form the bearing for the stem, it will be understood that the watchcase part is not only usually too thin to form an adequate bearing as above noted but 5 is usually made of a relatively soft metal such as gold, silver, platinum or the like, not adapted to form a suitable bearing, whatever its extent may happen to be. Also it should be well understood that in a great many watchcases the opening 14 is not formed for the stem to fit it at all but is left in the case as formed, in the manner previously pointed out. It is of course desirable that the support member 18 should be of material hard enough to add to the life of the bearing 10 over that permitted by the ample area of the bearing; and it is also desirable that the member should be of material that will well resist corrosion. Accordingly, though ordinary steel affords the hardest bearings, it is more desirable 15 to use a rustproof material, such as brass, bronze, German silver or any one of a large number of corrosion resisting alloys known in the art. Stainless steel may be used. It will be understood 20 of course that I am not limited as to the material used in the member 18.

In the cases of two-piece construction, as shown in Fig. 5, the back 11a receives the bezel or front 12a in telescoping relation; the back 11a being formed with a shoulder 22a, all around, 30 of the thickness of the metal of the bezel 12a. These cases usually are made with two parts 11a and 12a having notches 14a and 14b respectively which register to leave an opening for the movement stem when the case has been assembled. However, in the usual quantity production, when the case parts 11a and 12a are formed of sheet metal, these notches are allowed to have merely the irregular shape incident to drawing 35 up the material after the notches have been 40 formed in the blanks, with the notches amply large to avoid accurate fitting around the stem.

With watchcases of this construction, my invention is incorporated by bringing the back 11a and bezel 12a into assembled relation, and then 45 accurately enlarging the opening formed by the notches 14a and 14b in accurate alignment with the bearing in the watch movement in the same manner as the opening in the center of the three-piece case is treated, according to the previous 50 description. Then the support member 18 is formed to accurately fit the opening thus provided, with its flange 19 fitting against the edge surfaces of the case portions 11a and 12a as permitted by the shoulders 22a which brings these 55 surfaces substantially in a single plane.

I have shown modifications in which my invention is embodied, but it will be understood that other modifications will arise, and what I 60 claim is:

1. In a watchcase construction, in combination with a watchcase having an opening through which extends the stem of a watch movement mounted in the case, said opening being of greater diameter than the part of the stem there-in, a support and sealing member comprising a cylindrical body portion extending through and frictionally held in said opening, with a central axial passage around which its walls are continuous from end to end, forming a bearing for 70 the stem interiorly and a sealing contact with the case-opening edge exteriorly, said member also comprising a flange at the outer end of the support member having a bearing against the exterior surface of the case around said opening, 75

the opposite end of said body portion being devoid of flange or other extension, permitting said support member to be inserted from the exterior of the case into said opening, said opening having such accurate concentricity with the stem that said support member, held in said opening due only to its frictional contact therein and said bearing of said flange against the case, operatively supports the stem and seals the watch-case therearound, for the purposes set forth.
